UNITED STATES PATENT OFFICE.

GEORGE J. LOEPPER AND PAUL B. HAUSDOERFER, OF INDIANAPOLIS,
INDIANA.

ATTACHMENT FOR HIGH-SPEED GOVERNORS.

SPECIFICATION forming part of Letters Patent No. 663,235, dated December 4, 1900.

Application filed June 7, 1900. Serial No. 19,422. (No model.)

To all whom it may concern:

Be it known that we, GEORGE J. LOEPPER and PAUL B. HAUSDOERFER, citizens of the United States, residing at Indianapolis, in the county of Marion and State of Indiana, have invented new and useful Improvements in Attachments for High-Speed Governors, of which the following is a specification.

Our invention relates to an improvement on centrifugal high-speed governors, and especially to that class of high-speed governors for which Letters Patent have been granted to us on the 27th day of December, 1898, being numbered 616,678.

Our object of improving said invention is to provide an attachment to our previously-patented invention that will increase the speed of an engine to a higher degree of speed while the engine is in motion without being compelled in order to obtain said results to either change the size of the driver-pulley on the governor or the driving-pulley on the engine. In our former invention we obtained speed to the engine of approximately one hundred revolutions per minute with our new high-speed attachment applied. We can, if desired, increase the speed to approximately four hundred revolutions per minute without inconvenience, all of which is greatly desired in the use of steam and gas engines. We accomplish these objects by means of the device herein described, and illustrated in the accompanying drawings, wherein like characters of reference indicate like parts of our invention in the several figures.

In the drawings, Figure 1 is a front elevation of our invention, showing our high-speed attachment applied to our governor patented December 27, 1898, No. 616,678, in the United States of America. Fig. 2 is a horizontal section of said attachment on the line X X of Fig. 1 looking downward. Fig. 3 is a horizontal section on the line a a of Fig. 1. Fig. 4 is a side elevation showing the lower tension device, the upper portion of the invention being left off from line b b upward.

a is the valve-body of the governor, and b the valve-rod, which extends downward into said body and upward into the hollow spindle 5 and has its upper end attached, as indicated at c, to a collar d, which rests upon

and partakes of the longitudinal movements of a cap e, the action of which is controlled to raise and lower the valve-stem by the governor-balls having their lower arms secured thereto at f. A bevel-pinion g, loosely mounted on the hollow spindle or standard 5 and held against vertical movement by suitable devices, engages a bevel-pinion h, which is fixed on a transverse shaft i. Connected with the valve-stem b is a means which regulates the speed of the engine and provides an automatic shut-off, said means comprehending a lever j, the longer arm of which engages the valve-stem, a spring-tension device which acts on said lever, and which tension device includes a ratchet k and a pawl l for maintaining tension on said lever and which also includes means for adjusting the tension of the spring. Said pawl l is in practice arranged in the path of a striking device which if the belt operating the governor breaks or becomes otherwise disengaged will automatically engage said pawl l, and thus release the tension-spring and allow the lever, with the valve-rod, to move so as to close the steam-ports in the cylinder.

As thus far described the invention is comprehended in the one patented to us and above referred to; but practical experience with the patented device has disclosed the fact that when the tension-spring is wound up to its extreme limit, which will then produce the highest speed obtainable therefrom, the friction on the sliding cap e and collar d is increased to an extent which prevents free working of the parts. We have discovered that by applying an upper spring-tension device in addition to the lower spring-tension device the lower tension-spring is partly relieved, as is also the friction on said cap and collar, thus equalizing the friction between the bearings. Thus the addition of the upper tension device results in an increase in the speed which may be obtained and also diminishes the friction on the bearings in the governor. The lower spring-tension device is preferably modified in construction to that hereinafter described and is itself obviously capable of action alone where a relatively low speed is desired.

The manner of constructing our new at-

tachment to high-speed governors is as follows:

The hollow spindle or standard 5 is provided on its upper end with an extension-rod 4, which may be screwed into the end of standard 5, or said standard 5 and hollow spindle 4 may be constructed of one piece of steel, the lower screw end to be screwed firmly into the yoke-head 3, applied in the same manner as in our Patent No. 616,678, dated December 27, 1898. The upper end of the extension-rod 4 is threaded to receive the adjusting thumb-nut 3, and said extension-rod 4 is provided with an elongated slot or feather-seat 4^a. 15 2 is a collar loosely mounted around spindle 4 and having a feather 1 fitting into the elongated slot 4^a of extension-rod 4, whereby it is prevented from revolving with the rotating parts and at the same time may be adjusted upward and downward when so forced by means of the thumb-adjusting-nut 3. (See Fig. 1.)

5^a is an ornamental socket-collar loosely mounted on rod 4. Into said collar fits loosely 25 the feather-collar 2.

6 is a flanged collar loosely fitted around spindle 4.

Between the faces of collars 5^a and 6 are placed the tension-springs 7, formed in yoke 30 shape, with their arms extending downward and their ends bearing against the governor-ball arms 19 19.

The collar 5^a and flanged collar 6 are united face to face, with the springs 7 between them, and they are held in position by means of set-screws 8, which pass through threaded lugs 9, cast vertical on flange 6.

On the lower face of collar 6 are cast diametrically to each other the downward-projecting arms 10, which fit into corresponding 40 openings 11 of the flanged governor head or cap 14, to which the upper ends of the ball-arms 19 are attached, (see Fig. 3.), thus imparting a rotary motion to the upper tension attachment and at the same time permitting said attachment as a whole to slide upward or downward on spindle 4.

As can readily be seen, we need but to turn thumb-screw 3 downward or upward to increase or decrease tension on arms 19 as may be required to increase the speed of the engine independent from the lower tension-springs 28.

Instead of applying one spring, as in our former invention, we apply two springs for the lower tension, which are loosely mounted on the shaft 23. The inner and outer ends of said springs are turned at right angles to the center of shaft 23. These inner ends are 55 made to slip into the sockets 29 and their turned-up ends into slots 13 of sockets 29. The outer end of said spring slips into sockets of hand-wheel 31 on the left side and at the right side into socket 30. Both socket 60 and hand-wheel are provided with a slot into which the upturned ends of the springs fit

and are thus held in position. Through this arrangement we are enabled to apply one right and one left wound spring, and by turning them with the hand-wheel 31 we produce 70 tension through yoke 12 on the valve-stem in a vertical direction without side friction, which has been found to be a serious objection in cases where only one spring is applied. As can readily be seen, the object of two separate tension devices on one governor serves 75 the purpose to lessen the friction on the regulating mechanism of a high-speed governor and to reduce said friction to a minimum.

The parts most important to a sensitive 80 high-speed governor are the adjusting parts to prevent the engine from becoming uncontrollable in case the belt should drop off. We claim as an entire safety against such accidents the application of two tension devices 85 on our governor, one for exceeding high speed and the other for lower speed, but both depending on each other to produce the desired result.

Having thus described our attachment for 90 high-speed governors, its advantages and objects, that which we claim as new, and desire to secure by Letters Patent of the United States, is—

1. The combination with a valve-rod and 95 its valve, of controlling devices for said valve, embracing a rotatable head, a device connected with said rod so as to move therewith and have rotatable movement, relatively thereto, with said head, means for rotating said device, ball-carrying arms connecting said device and head together, a tension means connected with said valve-rod, and a second tension means connected with said ball-carrying arms. 105

2. In a governor, the combination with the standard, head, ball-arms connected with said head, and a controlling device, of a supplemental tension device embracing springs to engage said ball-arms, a spindle projecting 110 from said standard, a collar loosely mounted on said spindle and having arms engaging openings in said head, said collar also engaging said springs, and means acting on said collar to adjust the tension of said springs. 115

3. In a governor, the combination with ball-arms and balls, a rotatable and slid able cap with which the lower ends of said ball-arms are connected, and a valve-rod connected with said cap, of a lower spring tension device connected with said rod, and an upper spring tension device, comprehending a revoluble member to which the upper ends of the ball-arms are attached, and tension-springs engaging the ball-arms, substantially 120 as described.

4. In a governor, the combination with the valve-rod, ball-arms and balls, a cap with which the lower ends of the ball-arms are connected, said cap being also connected with 125 said valve-rod, and a head with which the upper ends of the ball-arms are connected, of

a lower spring tension device having adjusting means therefor, and an upper spring tension device embracing springs engaging said ball-arms, a vertically-adjustable rotatable collar carrying said springs, and means for fixing said collar in adjusted position.

5. In a governor the combination with the ball-arms and a controlling device therefor, of a vertically-movable rotatable collar, 10 springs carried thereby and engaging said ball-arms, a vertically-adjustable non-rotative collar, and threaded means for adjusting said collars and locking them in adjusted position to thereby regulate the tension of 15 said springs.

6. In a governor, the combination with a standard having a head and a threaded spindle, ball-arms connected with said head, and a controlling device, of a supplemental 20 controlling device, comprising a vertically-adjustable collar, a second collar connected therewith, arms projecting from the first-mentioned collar into grooves in said head, springs carried by said collars and bearing against 25 said ball-arms, a vertically-adjustable collar bearing upon said second collar and keyed to said spindle, and an adjusting-nut threaded upon said spindle and engaging the latter collar.

30 7. The combination, in a governor, with a valve-rod and its valve, of a rotatable head, a slide device which partakes of the movements of the valve and has rotatable movement, independently thereof, with said head, 35 ball-carrying arms connecting said head and device together, tension-springs acting on said arms, a device rotatable with said head and arms and adjustable relatively thereto and carrying said springs, and means for maintaining the latter device and springs in ad- 40 justed position.

8. The combination, in a governor, with a standard having a fixed head and a threaded spindle, of a vertically-adjustable device hav- 45 ing arms projecting into grooves in said head, springs carried by said device and engaging said ball-arms, a collar feathered to said spindle and bearing upon said device, and an ad-

justing-nut threaded upon said spindle and engaging said collar.

9. The combination with a valve-rod and its valve, of means for controlling the actions of the same, comprising a rotatable and slide- 50 able cap, means for rotating said cap, a collar attached to said rod and engaged with said cap, a tension means operatively connected with said valve-rod, a rotatable head, ball- carrying arms connecting said device and head together, and tension-springs connected with said arms.

10. The combination with a valve-rod and its valve, of means for controlling the actions of the same, comprising a rotatable and slide- 55 able cap, means for rotating said cap, a collar attached to said rod and engaged with said cap, an adjustable tension means operatively connected with said rod, a rotatable head, ball-carrying arms connecting said head and cap together, tension-springs acting on said arms, rotatable means carrying said tension- 60 springs and adjustable relatively to said head, and means for maintaining the same in ad- justed position.

11. The combination with a valve-rod and its valve, a tension device operatively connected with said rod, a standard, a rotatable head, means for rotating the same, a rotatable and slide- 75 able cap, a collar attached to said rod and engaged with said cap, and ball-carrying arms connecting said head and cap together, of a threaded spindle, a vertically- adjustable device having arms projecting into grooves in said head, springs carried by said device and engaging said ball-arms, a collar feathered to said spindle and bearing upon 80 said device, and an adjusting-nut threaded upon said spindle and engaging said collar.

In testimony whereof we have hereunto set our hands in the presence of two subscribing witnesses.
